UNITED STATES PATENT OFFICE.

HARRY MACMILLAN, OF PHILADELPHIA, PENNSYLVANIA.

SAFETY CHECK VALVE.

Application filed December 14, 1920. Serial No. 430,791.

My invention relates more particularly to safety check valves for use where explosive mixtures of gas are used in internal combustion engines, gas ranges, furnaces and the like, and has for its object the prevention of what is known as back-fire in such apparatus.

Another object of my invention is to so construct the valve that there shall be the least resistance to the flow of the gases through the valve.

With these ends in view, this invention consists in the details of construction and combination of elements hereinafter set forth, and then specifically designated by the claims.

In order that those skilled in the art to which this invention appertains may understand how to make and use the same, I will describe its construction in detail, referring by numerals to the accompanying drawing forming a part of this specification, in which,

Figure 1 is a plan view of the check valve made in accordance with my improvement, broken away to illustrate the internal construction thereof.

Figure 2 is a section of the same on the line 2—2 of Figure 1.

Figure 3 is a fragmental end view of the same.

In carrying out my invention, as here embodied, 1 represents the lower member of the check valve and 2 the upper member; the inlet 3 is threaded as is the outlet 4, the two members are held together by the screws 5, and a gasket 6 is inserted to make the joint gas proof. The lower member 1 has a recess 7 in which is placed a double wire gauze 8 and 9, separated or spaced by a ring 10 to which the gauze can be soldered, the ring being fitted tightly in the recess. Above this recess is the seat which can be made as shown with a flat portion 11, a raised portion 12, and another flat portion 13, or this seat can be waved with two or more depressions, 14 being a ring of leather or other suitable material which may be cemented to this seat. The disk 15 is made as light as possible, has convolutions conforming with the seat and can be dished in the center to give greater strength. It is held down by the slight pressure of the spring 16, as shown, which also tends to center it. Gauzes 17 and 18 are attached to a ring 19 and fitted into the recess 20 of the upper member 2. The mem-

ber 2 is provided with a blow out plate 21 of the same or similar material as the valve casing members and which has only the opening 23 leading to the chamber 24 above the gauze 18 but this opening is made of considerably greater area than the outlet 4. The pocket 25 may vary in shape but the opening 23 must be below the level of the bottom wall of the outlet 4.

It is evident that the inlet and outlet can be in a more or less vertical plane if desired.

The use of an explosive vapor, that is, a mixture of gas and air in well known proportions, is not considered safe in driving internal combustion engines for the reason that there is a chance of a lean mixture of gas igniting, not exploding, in the cylinder; this fire may remain and when the admission valve is again opened, it may ignite the incoming gas and cause it to back-fire. Now, if there is any considerable volume of such explosive gas that the back-fire can reach, the result may be a serious explosion and they have been known to occur.

When my improvement is used the check valve disk 15 is always seated, unless there is a considerable suction from the engine which there is not if gas is burning in the cylinder and therefore only the gas between the check and the engine can be ignited; there is however still the remote chance that this fire may not be out before the next suction stroke occurs. This will draw gas through the check and the fire might follow the incoming gas back to the tank and explode it. I have therefore inserted screens made of copper or brass wire mesh in the passages leading to and from the check, and have designed these so that they have a relatively abnormal area in comparison with the area of the feed and discharge pipes so that the flow of the gas shall be very slow through the screens.

It has been recognized for the past hundred years that such a screen or gauze will not allow a flame to pass it unless the speed of gas exceeds six feet per second, this being due to the cooling effect of the large surface of metal in proportion to the size of the holes left in such a gauze, and this effect does not seem to be changed if the temperature of the gas is raised to over 120 deg. F. It is also recognized that two or more such screens, if clean, are many times more effective than a single screen. By properly pro-

portioning the screen area to the flow of gas I can insure the prevention of any flame passing.

As the above description stands the valve 6 might not yet be safe against a distinct explosion of gas in the outlet. I have therefore provided the pocket 25 into which the first effect of an explosion, as a rapidly moving body of flame is understood, will be projected, because it has been demonstrated that 10 such a movement is projectile and tends to follow a straight line, but, if pocketed, will at once knock itself out.

The screens have another important function, for as the gas and air pass them they are sieved and the mixture made much more intimate than if the same proportions of gas and air are simply drawn through a tube where the slight friction of the walls 20 is the only disturbing factor to the straight flow; and the better the air and gas vapor are mixed the more effective their joint explosion is in performing work in the cylinder.

25 Of course I do not wish to be limited to the exact details of construction here shown, as these may be varied within the scope of the appended claims without departing from the spirit of my invention.

30 Having thus fully described my invention which I claim as new and useful is:—

1. A safety check valve including a casing having an inlet, an outlet and a seat between said inlet and outlet, a valve disc 35 coacting with said seat, and an apertured blow-out plate located between the outlet and the valve seat and forming with the walls of the casing a pocket in alignment with the outlet.

40 2. A safety check valve including a casing having an inlet, an outlet and a seat between said inlet and outlet, a valve disc coacting with said seat, and a blow-out plate located between the outlet and the valve 45 seat and forming a pocket between it and the walls of the casing, said pocket being in

alignment with the outlet and said plate having an aperture therein adjacent the outlet.

3. A safety check valve including a casing having an inlet, an outlet and a seat between said inlet and outlet, a valve disc coacting with said seat, and a blow-out plate located between the outlet and the valve seat with the portion of said plate adjacent the 55 outlet lying in a plane below said outlet, said portion having an aperture therein of greater area than said outlet, said blow-out plate forming with the walls of the casing a pocket beyond the aperture in alignment 60 with the outlet.

4. A check valve comprising a casing having a passageway therethrough, a valve disc within the passageway for normally closing said passageway and a pocket in said passageway on one side of the valve disc.

5. A check valve comprising a casing having an inlet and an outlet, a valve seat within the casing and between the inlet and the outlet, a member to coact with the valve seat, and a pocket within the casing on one side of the valve seat.

6. A check valve comprising a casing having a passageway therethrough, a valve member within the passageway for normally closing the passageway, a spring to actuate the valve member to normally close the passageway and a pocket in said passageway on one side of the valve member.

7. A check valve comprising a casing having an inlet and an outlet, a passageway connecting the inlet and outlet, a valve seat within the passageway and a pocket in the passageway between the valve seat and the outlet.

8. A check valve comprising a casing having an inlet and an outlet, a passageway connecting the inlet and the outlet, a valve between the inlet and the outlet, and a pocket formed in line with and at the inner end of the bore of the outlet.

HARRY MACMILLAN.
